Patented Nov. 16, 1926.

UNITED STATES PATENT OFFICE.

HOWARD M. WOLF, OF MUNCIE, INDIANA, ASSIGNOR TO THE BRODERICK COMPANY, A CORPORATION OF INDIANA.

METHOD OF FORMING INSIDE-BOILER-WRAPPER SHEETS.

Application filed August 8, 1925. Serial No. 49,045.

The invention relates to return tubular boilers and has for its object to produce an inside wrapper sheet comprising a crown sheet and sides or leg elements the rear ends 5 of which extend above the crown sheet, without employing riveted joints and without making in the blank any bends that must again be straightened.

The invention is illustrated in the accompanying drawing in which Fig. 1 is a vertical longitudinal section; Figs. 2 and 3 are transverse sectional views on lines 2—2 and 3—3 of Fig. 1, respectively; Fig. 4 is a view of a sheet used in forming a certain portion 15 of the boiler; Fig. 5 is the same sheet after a portion has been cut out; and Fig. 6 is the same sheet after it has been bent into the necessary shape.

The boiler is of the horizontal return 20 tubular type. It has an upper more or less cylindrical body portion from which extend downwardly lateral and end water legs enclosing a furnace space. The body portion is provided with fire tubes, some of which 25 carry the hot gases forward into the front smokebox, the others carrying it from this smokebox back to a rear smokebox.

The entire boiler illustrated in the drawings is, with the exception of the front and 30 rear smokeboxes, to all intents and purposes a single unitary structure of uniform thickness throughout and without any riveted or caulked joints.

To provide such a structure I use an outer 35 or main sheet 1, which, as will be seen particularly from Figs. 2 and 3, is of an inverted U-shape. The middle portion of this sheet forms the upper part of the cylindrical body and the straight downwardly extending portions form the outside of the lateral water legs.

The inner wall or wrapper sheet of the boiler is formed of a second sheet 2 which also has a generally inverted U-shape except 45 that the upper part is given a reverse downward curve as clearly shown at 3 in Figs. 2 and 3. The straight downwardly extending parts are parallel to the corresponding parts 50 of sheet 1 and spaced from them. The bottom of the water legs so formed is closed by portions 4—4 of the sheets 2 which are bent outwardly to meet the lower extremities 55 of the sheet 1. They are welded to these sheets along the lines 5—5.

The upper rear part of the inner wrapper

sheet 2 is cut away, leaving only the inner walls of the two water legs. To the upper edges 6—6 thus formed are welded sheets 7—7 which form the sides of the upper auxiliary combustion chamber. These sheets 60 have a curved outline 9 from their lower rear corners to their upper forward corners.

Closing the rear ends of sheet 2 and the curved edges 9 of sheets 7—7 is the sheet 12. This sheet has a straight lower portion and 65 a curved upper portion. The straight portion is spaced from the parallel sheet 13, which closes the rear end of sheet 1 and which is welded to it along line 11^a. The bottom of the rear water leg thus formed is 70 closed by a bent-over portion 14 of sheet 12, which is welded to 13 along the line 15.

A rear flue sheet 10 is welded to the rear edge of the cut-out portion of sheet 2, and to the front edges of sheets 7—7 and 12. It 75 is welded to the latter along line 11, and to the sheet 2 along the line 11^b.

The front end of sheet 1 is closed by a sheet 16 welded to sheet 1 along the line 17. A sheet 18 parallel to 16 and spaced from it 80 closes the front of sheet 2, being welded to it along the line 19. This lower portion 20 is bent forward to close the lower end of the water leg, being welded to sheet 16 along the line 21.

Through the front water leg extends the short oval thimble 22, forming an opening 85 for firing the boiler, its ends being welded to the edges of the holes in the two sheets.

Flues 23 extend from sheet 10 forward to sheet 16, being rolled or otherwise secured to said two sheets. Flues 24 connect the front sheet 16 to the rear sheet 13, being likewise secured to these two sheets by 90 rolling or any other desired method. A front smokebox 25 is secured to sheet 16 in such manner as to cover the forward openings of the flues 23 and 24, and a rear smokebox 26 is secured to rear sheet 13 over the rear ends of flues 24. The smokebox 26 100 has an opening 28 for connection to the stack.

The flat legs around the four sides of the fire box are stayed at intervals by means of the stays 26—26. In addition stays 27 105 connect the flat portion of sheet 1 as shown. The boiler may be used for merely heating water or for the generation of steam, as desired. The necessary connections for introducing water and for taking off the steam 110

or the heated water will of course be provided.

The products of combustion travel forward through flues 23 and then backward through flues 24 into smokebox 26, from which they escape through the stack to the connection 28.

In cutting or shaping the parts for the construction of this boiler the preparation of outer sheet 1 needs no particular mention or description. The sheet 2 is cut from a rectangular sheet of the necessary dimensions A and B, as illustrated in Fig. 4. From this sheet a portion is cut out as indicated at C in Fig. 5. The sheet is then bent so that the portion E assumes the shape shown in Fig. 6 and the vertical side portions assume parallel positions as illustrated, the curves at D—D being gradually rounding ones. The bottom portions 4—4 are turned outwardly at right angles, the small sheets that form the sides of the upper auxiliary combustion chamber are then welded to the upper edges of the vertical side portions, just in rear of the crown sheet. It

will thus be seen that no part of this completed inside wrapper sheet is required to be bent and then again straightened or flattened in the process of producing the sheet.

The remaining sheets are of such simple form that they need no further description. The whole structure is assembled and the abutting edges welded by autogenous or other preferred means.

What I claim is:

The method of forming an inside wrapper sheet for a boiler, which consists in cutting out of a flat sheet one end of a central panel extending along one of the main axes of the sheet, bending the flat sheet to shape the remaining portion of said panel into a curved crown sheet and the side portions of the sheet into parallel legs extending beyond one end of the crown sheet, and welding a plate to the top edge of each of the leg extensions to increase the effective heights of such extensions.

HOWARD M. WOLF.
